(57) **CLAIM**

The ornamental design for a cup turner tumbler, as shown and described.

DESCRIPTION

FIG. 1 is a perspective photographic view of a cup turner tumbler, showing my new design;

FIG. 2 is a top plan photographic view thereof;

FIG. 3 is a bottom plan photographic view thereof;

FIG. 4 is a right side elevation photographic view thereof;

FIG. 5 is a left side elevation photographic view thereof;

FIG. 6 is a rear elevation photographic view thereof;

FIG. 7 is a front elevation photographic view thereof;

FIG. 8 is another perspective photographic view thereof;

FIG. 9 is another perspective photographic view thereof; and,

FIG. 10 is another perspective photographic view thereof.

1 Claim, 10 Drawing Sheets(56)
